UNITED STATES PATENT OFFICE.

HERBERT E. PUTNEY, OF TOLEDO, OHIO, ASSIGNOR, BY DIRECT AND MESNE ASSIGNMENTS, OF THREE-FIFTHS TO MILTON D. PUTNEY, HENRY WILE, AND JESSIE L. WRITNER, OF SAME PLACE.

BRAKE MECHANISM.

SPECIFICATION forming part of Letters Patent No. 664,895, dated January 1, 1901.

Application filed March 30, 1900. Serial No. 10,738. (No model.)

To all whom it may concern:

Be it known that I, HERBERT E. PUTNEY, a citizen of the United States, residing at Toledo, in the county of Lucas and State of Ohio, have 5 invented a new and useful Improvement in Brake Mechanism, of which the following is a specification.

In the specification of Letters Patent No. 581,490, dated April 27, 1897, I have described 10 an improved brake mechanism applicable to cars wherein brake-shoes are simultaneously moved into and out of frictional contact with disks secured to the car-axles by mechanism simultaneously actuating the shoes. Without departing from the principle of the brake mechanism therein described my invention relates to improvements thereof, and has for 15 its objects to simplify the construction and application of the brake mechanism, increase 20 its effectiveness, and establish it in better relation to other parts of the car mechanism, with reference to accessibility to both car and brake mechanism; furthermore, to provide 25 noiseless friction-surfaces for the brake readily renewable when worn. I accomplish these 30 objects as illustrated in the accompanying drawings and hereinafter described.

In the drawings, Figure 1 is a diagrammatic plan view of my invention applied to a 35 car-truck. Fig. 2 is a longitudinal section through a car-truck, showing a brake bar and shoe in side elevation. Fig. 3 is a transverse section of a car-wheel and of a brake-shoe as applied thereto. Fig. 4 shows one 40 section of a shoe. Fig. 5 is a longitudinal section through a car-truck, showing a side elevation of a shoe and brake-bars as applied to a single axle thereof; and Fig. 6 shows a modified form of brake-shoe.

Referring to the drawings, 11 are the axles 45 of a car-truck, having wheels 2 permanently secured thereon, each provided with a concentric disk 3 on its inner face and preferably cast integral therewith and an elongated inwardly-extended hub 4.

5 are supporting-bars, resting in position near and parallel to the wheels, across beams of the truck-frame, to which are secured 50 brake-shoes 6, having one face 7 adapted to

frictional engagement with disks 3 of wheels 50 2 and provided with a central orifice 8 of a diameter greater than the diameter of the hub 4 and adapted to receive the hub centrally without contact therewith. Shoes 6 are formed of sections 9 and 10, each in cut to 55 form one-half of orifice 8 and having complementary overlapping portions 11 and 12, respectively, which are provided with coincident orifices, through which are inserted bolts 13, by which the sections are firmly 60 secured together around an axle 1, with the heads of bolts 13 countersunk in the frictional face 7 of the shoe. The sections are also provided with ribs 14 on the opposite side to increase the rigidity of the shoe and with 65 oppositely-projecting shanks 15, one or both of which are adapted to be bolted to a supporting-bar 5 and provided with a boss 16, according as the shoes are designed to be attached to the bars in pairs, as shown in 70 Figs. 1 and 2, or singly, as in Figs. 5 and 6. Centrally through the bosses 16 and the shanks 15 are orifices 17, which are inwardly threaded with right or left threads of equal pitch, according to the position of the shoe, 75 all of those on the same side of the car being relatively right or left threaded in respect to those in the shoes of the opposite side. Between the shoes 6 of each axle and connecting them are shafts 18, in threaded engagement therewith through the orifices 17. One end of shafts 18 is right and the other 80 left threaded to adapt them to such engagement. Shafts 18 are provided with suitable pulleys 19, by which all the shafts 18 of each 85 car are revolvably connected to each other and to the brake-operating mechanism, preferably by wire-rope belting 20, riveted around the pulleys; but crank-levers may be substituted for the pulleys and connecting-rods for 90 the belting when better serving the purpose of rotating the shafts 18 in unison. The shafts 18 are made of such length that when in threaded engagement at each end with a brake-shoe the frictional faces of the shoes of 95 each axle may be held at such distance from the face of their respective wheel-disks that one revolution, more or less, of shafts 18 will

simultaneously advance them into or retract them from direct contact with the disks of the wheels, according to the direction in which the shafts are rotated, and the several shafts 5 of a car being rotated in unison all the shoes of a car will be advanced or retracted in unison. Shoes 6 thus connected are supported by bars 5, secured thereto as described, resting across the central beams 21 of a car-truck 10 when applied to all of the wheels of a street-car truck, as in Fig. 1, or on a central and end beam of the truck where applied to the wheels of a single axle, as in Fig. 5, or on the sand-plate or its equivalent of the trucks of 15 railroad-cars, the bars 5 being constructed in such form as may be best adapted for their own support and the support of the shoes in proper position for contact with the wheel-disks. Bars 5 are also provided with any suitable 20 means of preventing their longitudinal or vertical movement without limitation of their lateral movement by shafts 18, such as stops 22, (shown in Figs. 1 and 2,) and to prevent the lateral shifting on the truck of the 25 frame, formed of shoes 6, their connecting-shafts 18, and supporting-bars 5, spring-stops 23 of sufficient resistance attached to the supports of the bars, either between or outside the bars, adapted to yield to the retraction 30 or advancement of the bars under the pressure of screw-shafts 18 may be used.

The friction-disks 3 of the car-wheels are preferably provided with friction-plates 24, of indurated fiber or other suitable material, 35 secured thereto by bolts 25 through the web of the wheel, with the heads of the bolts countersunk in the friction-plates. Similar plates may also be attached to the bearing-face of the shoes 6 in a similar manner. By the use 40 of the plates 24, which may be renewed as required, the wearing of the wheel-disk or of the metal of both the wheel and the shoes is avoided and the noise arising from frictional contact of metal with metal is prevented.

45 The elongated hub 4 of wheel 2 is designed as a substitute for the collars ordinarily used in electric-railway car-trucks to confine the motor and prevent it from shifting its position on the axle. While its use for such purpose is preferable, it may be omitted from 50 wheels where motors are not attached to the trucks.

55 In Fig. 6 is shown a modified form of brake-shoe 6, longitudinally divided into sections 26 and 27, adapted to be bolted together around the axle. In this form while more effective with the sections combined it is operative with the section 27 omitted, the bosses 16 and shanks 15 for securing it to supporting-bars 5 being both integral with section 26.

60 By providing the wheels with friction-disks the necessity for independent disks on the axles is avoided, thereby reducing the number of separate parts required, economizing space, increasing the effectiveness of the brake, and rendering both brake and car

mechanism more accessible. By the construction herein described the brake mechanism is also more readily adapted to the various forms of truck-frames in use.

70

Having thus fully described my invention, what I claim to be new, and desire to secure by Letters Patent, is—

1. The combination of a frame, an axle journaled in the frame, a pair of track-wheels 75 fixed on the axle, each having a friction-disk integral with its inner web, concentric to the axle, friction-plates removably secured to the friction-disk of each wheel, a brake-shoe for each wheel, adapted for engagement with the plates of its disk and movably supported by bars secured to the shoes and resting on the frame, and means to simultaneously advance the shoes to engagement with the plates of the disks, and adapted to retract them again 80 from such engagement, substantially as shown and described.

2. The combination of a car-truck frame, an axle journaled in the frame, a pair of track-wheels fixed on the axle, a friction-disk integral with the inner web of each wheel concentric to the axle, a brake-shoe for each wheel, movably supported by bars secured to the shoes and resting on the frame and adapted for engagement with the disk of the wheel, 95 shafts connecting the shoes by right and left threaded engagement respectively therewith, adapted, when rotated in one direction, to advance the shoes to simultaneous engagement with the disks of the wheels, and, when rotated in the opposite direction, to retract them from such engagement, and means to rotate the shafts simultaneously forward or backward, substantially as shown and described.

105

3. The combination of a car-truck frame, a plurality of axles journaled in the frame, a pair of track-wheels fixed on each axle, a friction-disk fixed on the inner web of each wheel concentric with the axle, a brake-shoe for each wheel having a face adapted for engagement with the disk of its wheel, bars rigidly connecting the shoes on the same side of the frame in parallel and opposite relation to their respective disks and to the shoes and disks 115 of the other side, movably supported by the frame, shafts connecting the shoes of one side with shoes of the other by relatively right and left threaded engagement therewith, adapted, when simultaneously rotated in one 120 direction, to simultaneously advance the shoes of both sides of the truck outwardly to engagement with their respective wheel-disks, and, when rotated in the opposite direction, to retract them from such engagement, and 125 means to simultaneously rotate the shafts forward or backward.

4. The brake mechanism herein described, comprising car traction-wheels mounted on axles journaled in a frame, disks integral with 130 the inner webs of the wheels concentric to their axles, friction-plates removably secured to

the disks, bars, movable laterally, supported by the frame on opposite sides thereof in parallel relation, brake-shoes secured to the bars and supported thereby in position to contact with the plates of the disks, and means connected to the shoes adapted to simultaneously advance each shoe into frictional contact with the plate of a wheel-disk, and again retract them from such contact, all constructed and

operating substantially as shown and described.

In witness whereof I have hereunto set my hand this 22d day of March, A. D. 1900.

HERBERT E. PUTNEY.
